Atty.

UNITED STATES PATENT OFFICE.

ARTHUR ROBERTS, OF EVANSTON, ILLINOIS, ASSIGNOR TO AMERICAN COKE & CHEMICAL COMPANY, OF CHICAGO, ILLINOIS, A CORPORATION OF MAINE.

HEATING-WALL FOR COKE-OVEN AND THE LIKE.

1,399,275.

Specification of Letters Patent.

Patented Dec. 6, 1921.

Original application filed September 15, 1916, Serial No. 120,351. Divided and this application filed January 27, 1919. Serial No. 273,230.

To all whom it may concern:

Be it known that I, ARTHUR ROBERTS, a citizen of the United States, residing at Evanston, in the county of Cook and State of Illinois, have invented certain new and useful Improvements in Heating-Walls for Coke-Ovens and the like, of which the following is a specification.

The present invention has to do with certain improvements in heating walls for coke ovens and the like, although it will presently appear that the features of the invention are in no wise limited to use in connection with heating walls, but may be used with equal advantage in the construction of other coke oven walls.

In my co-pending application for Letters Patent of the United States on improvements in coal distillation retorts, Serial No. 120,351, which was filed September 15, 1916, I have shown a construction of coke oven wall which is provided on its interior portion with a meshwork of interconnected gas passages extending in zigzag fashion throughout the desired portion of the wall. The wall construction illustrated in the said application is one which is built up from blocks notched in a peculiar manner, so that, when said blocks are set together in the construction of the wall, the aforesaid notches will coöperate to provide the desired network or meshwork of interconnected passages.

This application is a division of the aforementioned application, Serial No. 120,351, and has to do particularly with the construction of the wall and the blocks from which it is built. The wall and block construction to which this invention relates are very well adapted for use in the construction of vertical retort coke ovens of that type in which the heating gases pass through the heating walls in a generally horizontal direction. One of the objects of the invention is to provide a heating wall construction in block form, in which the gas passages are of such form that gases flowing sidewise or in a generally horizontal direction will be caused to swing back and forth in a zigzag fashion, and will thus be caused to impinge with violence repeatedly against different portions of the wall.

Another object of the invention is to so form the walls and the blocks from which

they are constructed that a similar result will be secured in case the gases are caused to traverse the wall in a generally vertical direction.

Other objects and uses of the invention will appear from a detailed description of the same which consists in the features of construction and combinations of parts hereinafter described and claimed.

In the drawing:

Figure 1 shows a horizontal fragmentary section through a portion of a heating wall embodying the features of the present invention, being a section taken on the line 1—1 of Fig. 2, looking in the direction of the arrows;

Fig. 2 is a fragmentary vertical section taken on the line 2—2 of Fig. 1, looking in the direction of the arrows;

Fig. 3 is a fragmentary vertical cross section taken on the line 3—3 of Fig. 2, looking in the direction of the arrows;

Fig. 4 is a detail plan view of one of the blocks used in the construction of the wall;

Fig. 5 is a detail side elevation corresponding to Fig. 4; and

Fig. 6 is a cross section taken on the line 6—6 of Fig. 5, looking in the direction of the arrows.

Referring to the construction shown in the several drawings, each of the blocks from which the wall is constructed extends through the wall from its face 7 to its face 8. The blocks are ordinarily laid up in courses in the manner shown in Fig. 2, and ordinarily said courses will extend in a horizontal direction.

Each block has the central portions of its four corners recessed as at 9, 10, 11, and 12, so that, when the different blocks are set together in the courses, the recesses of the various blocks will coöperate to provide a series of zigzag passageways 13 interconnected in both horizontal and vertical directions.

It will be observed that, when the courses break joints, as is shown in Fig. 2 in particular, the passages 13 are so related that gases traversing the wall in a generally vertical direction, are of necessity caused to baffle or swing back and forth in a zigzag fashion. In order to secure a similar result in case the gases traverse the wall in a generally horizontal direction, I have illustrated the following expedient: That is, the

lower central portion of each block is extended down below its lower end portions to provide a tongue 14, the tongue of each block entering the space provided by the upper recesses of the two adjacent blocks of the next lower course. The tongues 14 in this manner make it impossible for gases to traverse the wall in a generally horizontal direction without baffling back and forth so as to cause the gases to impinge with violence repeatedly against different portions of the wall.

While I have herein shown and described only a single embodiment of my invention, still it will be understood that I do not limit myself to the said embodiment, except as I may do so in the claims.

I claim:

1. A coke oven heating wall comprising 20 courses of blocks, the courses breaking joints with each other, each block having its four corners recessed to provide, in conjunction with the adjoining blocks a series of passages extending in zig-zag fashion between the blocks of the successive courses, and each block having in its lower central portion a downwardly projecting tongue entering into the space between the recesses of the two blocks immediately below it, whereby gases 30 traveling lengthwise of the wall are compelled to pass around said tongues, and are therefore compelled to travel in a zig-zag fashion, substantially as described.

2. A coke oven heating wall comprising 35 courses of blocks, the courses breaking joints with each other, each block having corner recesses coöoperating with other blocks to provide passages between the adjacent blocks, and each block having a downwardly 40 projecting tongue on its lower portion depending into the block recess below, whereby gases traveling lengthwise of the wall are compelled to pass beneath the tongues, and are therefore compelled to travel in a zig-zag fashion, substantially as described.

3. A coke oven heating wall comprising 45 courses of blocks having their corners recessed, the recesses of the blocks of each

course communicating with those of the adjacent courses to provide a series of zig-zag 50 passages extending through the wall vertically, and each block having a downwardly projecting tongue entering into the recesses of blocks below, whereby there is provided a series of passages extending in zig-zag 55 fashion lengthwise of the wall, substantially as described.

4. A coke oven heating wall comprising courses of blocks, each block having the central portions of its side faces recessed and 60 having in the central portions of its four corners recesses communicating with the side recesses, the blocks of each course breaking joints with the blocks of the courses immediately above and below, the combined 65 width of the adjoining recesses of the blocks of a course being greater than the width of the opposing face of the block of the adjoining course, whereby communication is established through the wall in a zig-zag 70 manner in the direction of the courses through the medium of the corner recesses, and whereby communication is established through the wall in a zig-zag manner in a direction transversely of the course through 75 the medium of the side recesses, substantially as described.

5. A coke oven heating wall comprising courses of blocks, each block having recesses in the central portions of selected corners, 80 the end portions of the blocks of each course being in direct contact with the end portions of the blocks of the adjoining courses, the blocks of each course breaking joints with the blocks of the courses immediately 85 above and below, the combined width of each recessed opening of the blocks of a course being greater than the width of the opposing face of the blocks of the adjoining course, whereby communication is established through the wall in a zig-zag manner 90 in the direction of the course through the medium of the corner recesses, substantially as described.

ARTHUR ROBERTS.
